Primary Examiner — Jack Reickel*Assistant Examiner* — Bobby W Jones, II*(74) Attorney, Agent, or Firm* — Muncy, Geissler, Olds & Lowe, P.C.(57) **CLAIM**

The ornamental design for a bidet sprayer, as shown and described.

DESCRIPTION

FIG. 1 is a front elevational view of a bidet sprayer showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof; and,

FIG. 7 is a perspective view thereof.

The broken line showing of a bidet sprayer is included for the purpose of illustrating portions of the article and forms no part of the claimed design.

1 Claim, 7 Drawing Sheets(56)
